UNITED STATES PATENT OFFICE.

WILLIAM H. THOMMEN, OF PLYMOUTH, WISCONSIN, ASSIGNOR TO PLYMOUTH RADIO AND PHONOGRAPH CO., OF PLYMOUTH, WISCONSIN.

ANTIVIBRATING HORN.

Application filed October 4, 1924. Serial No. 741,583.

To all whom it may concern:

Be it known that I, WILLIAM H. THOMMEN, a citizen of the United States, and resident of Plymouth, in the county of Sheboygan and State of Wisconsin, have invented certain new and useful Improvements in Antivibrating Horns; and I do hereby declare that the following is a full, clear, and exact description thereof.

10 This invention relates to sound amplifying horns.

Objects of this invention are to provide a horn in which the neck portion is formed from a wooden block having a throat therethrough, whereby solid walls are provided between which the sound travels, such solid relatively heavy walls effectively eliminating vibration.

Further objects of my invention are to 20 provide a novel method of manufacturing a wooden horn, particularly the neck portion, by forming a throat channel in a solid block of wood by sawing it longitudinally into parts removing the innermost part and 25 thereafter gluing or fastening the parts together.

Further objects are to provide an amplifying horn which may be very cheaply formed from wood and may thus eliminate 30 harsh tones appearing in other types of horns, such as those formed from metal, and which is so constructed that it may be most easily manufactured.

An embodiment of the invention is shown 35 in the accompanying drawings, in which:

Figure 1 is a vertical longitudinal sectional view through the horn.

Figure 2 is a perspective view showing the neck portion in one stage of formation.

40 Figure 3 shows the neck portion in a further stage of formation.

Figure 4 is a plan view partly in section taken on the line 4—4 of Figure 1.

Figure 5 is a top plan view of the neck 45 portion.

In practising this invention, a longitudinal block of wood or fiber, such as shown in Figure 2, is sawed downwardly along divergent planes 1 and 2, to provide outer 50 upwardly thickening wedge members or sides 3 and 4, and a central upwardly tapering or narrowing wedge portion A. This central wedge portion is removed temporarily from the side members 3 and 4, and 55 is sawed along two diverging curving lines,

as indicated at 5 and 6, to provide a front member 7 and a rear member 8. The material included between these lines is removed and thus a diverging curving sound channel is formed.

It is to be noted from Figure 3 that the front portion 7 is shorter than the rear portion and is provided with a rounded lower edge, as indicated at 9. The rear portion underhangs or extends below the front portion 7 and is provided with a concave portion 10 positioned below the rounded lower end of the front portion 7.

The side wedge like members 3 and 4 are then glued or otherwise secured to the converging plane faces of the front and rear members 7 and 8, respectively, and thus a flared and curved sound channel 11 (see Figures 1 and 3) is provided in a solid heavy neck portion. This neck portion is a non-vibrating member and the extraneous sounds, notes and other disturbances produced in usual types of horns are wholly avoided by this construction, and a very pure and clear amplification of music or speech is given by 80 this horn.

The top of the neck portion is equipped with a clamping apertured member 12 which may be provided with a circular opening 13 to receive, for example, the receiver neck of 85 a wireless device or the tone arm of a phonograph. A slit 14 communicates with the aperture 13 and a screw 15 is employed to draw the member 12 into the desired intimate contact with the enclosed sound producing instrument. The bottom of the neck portion is secured to a board or other relatively short plate 16 which projects laterally beyond such neck portion and provides projecting feet which may be apertured at 17 90 (see Figure 4) to provide ready means of attaching the device to a suitable support.

The neck portion may be provided with an outwardly flaring attached horn having a relatively heavy bottom portion 18 and 100 a lighter upper portion 19 which may be slightly curved if desired. Preferably reinforcing cleats 20 are secured to the device at the junction of the outwardly extending portion with the neck portion, as illustrated 105 in Figure 1, to secure greater mechanical strength.

It will thus be seen that a novel form of amplifying horn has been provided which is non-vibrating, and which will insure a 110

clear amplification without distortion of the initial sound.

It will further be seen that a phonograph horn has been provided in which the neck portion thereof is formed from a solid block of material.

It will further be seen that a novel and simple method of making solid wall necks for amplifying horns from blocks of material such as wood or fiber has been provided, and it will be noted that this method may be very readily carried out in a simple and effective manner.

Although the invention has been described in considerable detail, it is to be understood that the invention may be variously embodied and is, therefore, to be limited only as claimed.

I claim:

- 20 1. The method of making the neck portions of horns comprising cutting an elongated rectangular block longitudinally along diverging planes to provide a central wedge and two outer wedges, sawing the central wedge along two diverging, longitudinally extending lines to provide front and rear portions, removing the material enclosed between said lines, and securing the front and rear members between the side members.
- 25 2. The method of making the neck portions of horns comprising cutting an elongated rectangular block longitudinally along diverging planes to provide a central wedge and two outer wedges, sawing the central wedge along two diverging, longitudinally extending lines to provide front and rear portions, removing the material enclosed between said lines, and securing the front and rear members between the side members.

- 30 2. The method of making the neck portions of horns comprising cutting an elongated rectangular block longitudinally along diverging planes to provide a central wedge and two outer wedges, sawing the central wedge along two diverging, longitudinally extending lines to provide front and rear portions, removing the material enclosed between said lines, and securing the front and rear members between the side members.

gated rectangular block longitudinally along diverging planes to provide a central wedge and two outer wedges, sawing the central wedge along two diverging, longitudinally extending lines to provide a front member having a rounded bottom portion and a rear member having a concaved portion spaced below said rounded portion, removing the material enclosed between said lines and securing the front and rear members between the side members.

3. A neck for a horn comprising a pair of side members of wedge shape with their thickest edges towards the throat of the horn and a pair of intermediate wedge-shaped members positioned between said side members with their thinnest portions towards the throat of the horn, said intermediate member being cut away on divergent lines to provide a gradual increasing space therebetween, one of said intermediate members being longer than the other and underhanging the lowest edge of the other of said intermediate members.

In testimony that I claim the foregoing I have hereunto set my hand at Milwaukee, in the county of Milwaukee and State of Wisconsin.

WILLIAM H. THOMMEN.
